FUSE CLIP CLAMP

Harold S. Creque and David B. Flower,
Philadelphia, Pa.

Application February 9, 1933. Serial No. 655,984

9 Claims. (Cl. 200—134)

Our invention relates to fuse clip clamps.

In practise, it is well known, that the conventional fuse clip when engaged with the terminal of a fuse does not sufficiently grip the terminal to establish a firm electrical contact, resulting in the creation of an arc between the terminal and fuse clip which causes heating and burning of the fuse.

It is an object of the invention to provide a clamp adapted to cooperate with the fuse clip, for clamping the clip securely in engagement with the terminal of the fuse, insuring a perfect electrical contact, so as to prevent the creation of an arc between the terminal and clip.

A further object of the invention is to provide a clamp of the above-mentioned character which may be quickly and readily engaged with the fuse clip and which embraces the whole of that portion of the clip which engages the terminal of the fuse, thus establishing a uniform contact between the terminal and fuse clip.

A still further object of the invention is to provide a fuse clip clamp having pivoted clamping jaws adapted to engage the fuse clip and a pivoted lever operable to move the jaws into firm clamping engagement with the fuse clip.

Another object of the invention is to provide a device of the above-mentioned character which is simple and durable in construction, reliable and efficient in use and inexpensive to manufacture.

Other objects and advantages of the invention will be apparent during the course of the following description.

In the accompanying drawing, forming a part of this specification and in which like numerals are employed to designate like parts throughout the same,

Fig. 1 is a side elevation view of the clamp,

Fig. 2 is an end view of the clamp, when in clamping engagement with a fuse clip,

Fig. 3 is a section taken on lines 3—3 of Fig. 2,

Fig. 4 is a top view of the clamp,

Fig. 5 is an enlarged section taken on lines 5—5 of Fig. 1,

Fig. 6 is a perspective view of the supporting plate for the clamping jaws, and,

Fig. 7 is a perspective view of one of the clamping jaws.

In the drawing, wherein for the purpose of illustration, a preferred embodiment of the invention is shown, the numerals 5 and 6, denote a pair of clamping jaws, which are formed from rectangular plates having their longitudinal edges bent to provide flanges 7, the flanges of each jaw having alined openings 8, above the intermediate

portion thereof. The jaws are pivotally supported on opposite sides of the supporting plate 9, which at each end is provided with upturned cross bars 10 and 11, which extend over the flanges 7, and have openings 12 and 13, respectively, adapted to aline with the openings 8 of the flanges and pintle pins 14 extend through the openings pivotally mounting the jaws on the supporting plate in confronting relation. The cross bar 11, extends upwardly to a point adjacent the upper ends of the jaws and is provided with a central slot 15, in its upper edge to receive one end of the clamping lever 16, which is pivotally supported by the pivot pin 17, extending through the handle and lugs 18, bent outwardly from the sides of the slot. The lever is constructed of insulation material and is of such length as to extend a substantial distance beyond the jaws when swung downwardly between the jaws into operative position.

The lower or gripping faces of the jaws are knurled, as at 19, and are of sufficient length and width to grip the entire portion of the fuse clip which contacts with the terminal of the fuse and each jaw face beneath the supporting plate 9, is formed with a shoulder 20 extending transversely of the face, over which the bent upper ends of the fuse clip engage, as shown in dotted lines in Fig. 2. The upper faces of the jaws are formed with opposed grooves or depressions 21, more clearly shown in Fig. 5, to receive and secure the lever 16 in operative position when swung downwardly between the jaws. There may be one or more sets of grooves extending transversely of the faces, at an angle to the vertical axis of the jaws, the lower set of grooves being slightly raised with respect to the upper set of grooves, so that by moving the lever from one set of grooves to the other the pressure on the jaws may be varied, thus permitting the gripping force of the jaws on the fuse clip, to be increased or decreased.

In use, the clamp is positioned with the gripping faces of the jaws engaged with the outer faces of the contacting portions of the fuse clip, which receive the terminal of the fuse, and upon swinging the clamping lever 16, downwardly between the upper faces of the jaws, the gripping faces of the jaws are moved inwardly, forcing the clip into firm electrical contact with the fuse terminal. The grooves 21, formed in the upper faces of the jaws, secure the lever in its operative positions, and as the lever moves from one set of grooves to the other, the pressure of the gripping faces on the clip is increased or decreased. The clamp, as illustrated, is designed particularly for use in con-

junction with knife type fuse clips, but it is apparent the same may be used with ferrule type fuse clips without material alterations.

It is to be understood that the form of the invention herein shown and described is to be taken as a preferred example of the same and that certain changes in the shape, size and arrangement of the parts may be made without departing from the spirit of the invention or the scope of the subjoined claims.

Having thus described our invention, we claim:

1. A fuse clip clamp comprising a supporting plate, a pair of clamping jaws pivotally mounted on opposite sides of said plate intermediate their length and a pivotally mounted lever carried by said supporting plate and adapted to swing between said jaws to move said jaws into clamping position.

2. A fuse clip clamp comprising a supporting plate, a pair of clamping jaws pivotally mounted on opposite sides of said plate intermediate their length and a lever having one end pivotally mounted on one end of said plate, said lever being adapted to swing between said jaws to move said jaws into clamping position.

3. A fuse clip clamp comprising a supporting plate, a pair of clamping jaws pivotally mounted on opposite sides of said plate, intermediate their length, a lever pivotally mounted on said plate adapted to operate between said jaws, to move said jaws into clamping position, and means for holding said lever in operative position.

4. A fuse clip clamp comprising a pair of pivotally mounted clamping jaws, a pivotally mounted lever operable between the jaws to move said jaws into clamping position, and means on said jaws for holding said lever in operative position.

5. A fuse clip clamp comprising a pair of pivotally mounted clamping jaws, and a pivotally mounted lever adapted to operate between

the upper ends of said jaws to move the jaws into clamping position, said jaws having depressions formed in the faces of their upper ends to receive and hold said lever in operative position.

6. A fuse clip clamp comprising a supporting plate having upturned cross bars at each end, a pair of jaws pivotally mounted between the cross bars on opposite sides of said plate, said jaws being pivoted intermediate their length, and a clamping lever having one end pivotally mounted on one of the cross bars, said lever being operable between the upper ends of said jaws to move the jaws into clamping position.

7. A fuse clip clamp comprising a supporting plate having upturned cross bars at each end, a pair of jaws pivotally mounted between the cross bars on opposite sides of said plate, said jaws being pivoted intermediate their length, and a clamping lever having one end pivotally mounted on one of the cross bars adapted to operate between the upper ends of said jaws to move the jaws into clamping position, the upper ends of said jaws having grooves to receive and secure said lever in clamping position.

8. A fuse clip clamp comprising a pair of opposed clamping jaws, means pivotally supporting said jaws and a lever having one end pivotally mounted on said means and adapted to swing between said jaws to move said jaws into clamping position.

9. A fuse clip clamp comprising a supporting plate having angularly bent cross bars at each end, a pair of jaws pivotally mounted on opposite sides of said supporting plate and a clamping lever having one end pivotally mounted on one of the cross bars, said lever being operable between the upper ends of said jaws to move the jaws into clamping position.
